B. B. BETTS.

TIE PLATE.

APPLICATION FILED MAY 13, 1913.

1,155,989.

Patented Oct. 5, 1915

UNITED STATES PATENT OFFICE.

BENJAMIN B. BETTS, OF ST. LOUIS, MISSOURI.

TIE-PLATE.

1,155,989.

Specification of Letters Patent.

Patented Oct. 5, 1915.

Application filed May 13, 1913. Serial No. 767,434.

To all whom it may concern:

Be it known that I, BENJAMIN B. BETTS, a citizen of the United States, and resident of St. Louis, Missouri, have invented cer-

tain new and useful Improvements in Tie-
5 Plates, of which the following is a specifica-
tion containing a full, clear, and exact de-
scription, reference being had to the accom-
panying drawings, forming a part hereof.

10 My invention relates to improvements in
tie plates, and the object of my invention is
to construct an improved combined running
and guard rail plate formed complete of one
piece of material and in such manner that
15 unaltered, standard running and guard rails
may be properly disposed and secured in
relation to each other, and to construct the
plate so that buckling caused by lateral
strains of rolling stock is wholly eliminated.

20 With the above purposes in view my in-
vention consists in certain novel features of
construction and arrangement of parts as
will be hereinafter described, pointed out
in the claims and illustrated by the accom-
25 panying drawings in which—

Figure 1 is a plan of a tie plate con-
structed according to my invention; Fig. 2
is an elevation of the plate shown in Fig. 1,
30 showing a running rail and a guard rail in
place; and Fig. 3 is an inverted plan of the
plate with certain parts broken away.

Referring by numerals to the accompa-
nying drawings: 4 designates the body of the
35 plate which is preferably of oblong-rectangu-
lar shape. As shown in the drawings the up-
per face at the right hand side of the plate
is employed as the rail-bearing surface 5 for
an unaltered, standard running rail 6. Pro-
jecting upwardly from the upper face of the
40 plate, contiguous to the right hand margin
of the rail-bearing surface 5, is a rail-base
shoulder 7 and formed through the plate
intersecting the rail-base shoulder 7 are one
or more spike openings 8.

45 In order to adapt the plate to varying
widths of rail-bases, I resort to the common
expedient of extending the spike openings
a slight distance to the left of the rail-base
shoulder 7. Formed on the top face of the
50 body of the plate to the left of the rail-
bearing surface 5 is a rail-bearing surface 9
which is in a plane above the plane of the
rail-bearing surface 5. Contiguous to the
left hand margin of the rail-bearing sur-
55 face 9 there is a rail-base shoulder 10 extend-
ing transversely of the surface 9. Formed

through the plate intersecting the shoulder
10 is a spike opening 11 and formed through
the body of the plate alone to the left of the
rail-bearing surface 9 are one or more spike 60
openings 12.

Formed on the right hand margin of the
body which constitutes the rail-bearing sur-
face 9, and overhanging the rail-bearing
surface 5 is a lip 13 which extends trans-
versely of the plate and is arranged to form
a securing means for the left hand margin
of the rail-base of the running rail.

14 designates a lip which is formed inte-
gral with the body constituting the rail-
bearing surface 9 and which projects toward
the left hand end of the plate to overhang
the rail-bearing surface 9 to provide a means
for securing the right hand margin of the
75 rail-base of the guard rail 15.

16 designates a brace formed integral with
the overhanging lips 13 and 14 and projects
upwardly and toward the right therefrom
to a point where it will engage the bottom
80 of the ball of the running rail 6.

For the purpose of saving material to re-
duce the cost of the plate there are formed
in the rail-bearing surface 9 the cavities 17,
and in order to reinforce the lips 13 and 14
I provide the integral ribs 18.

85 Projecting downwardly from the under-
neath face of the plate at about the longi-
tudinal center there is a transverse row of
ribs 19 which are shaped to embed in the tie
to prevent creeping of the plate and fur-
90 ther to stiffen the plate to prevent buckling.

At both ends of the plate and on the lower
face thereof are the transverse rows of ribs
20 which prevent creeping of the plate and
also rocking of the plate over the ribs 19.

95 In use I contemplate the employment of,
say for example, a one hundred pound run-
ning rail and an eighty pound guard rail.

In order that the balls of the two rails
may be separated a proper distance later-
ally relative to each other and without alter-
ing their structures it will be necessary to
overlap their bases, hence the rail-bearing
surface for the guard rail must extend over
the rail-bearing surface for the running
rail; and in order that the ball of the guard
rail be held above the plane of the ball of
the running rail the rail-bearing surface of
the guard rail must be above the running
rail bearing surface.

110 By the provision of the brace 16 for the
running rail the load of the rolling stock

is shifted to the center of the tie plate in order to prevent buckling which is common in plates where the load is carried directly by the rail to one side of the longitudinal center of the plate.

I claim:

1. A tie plate having overlapping rail seats adapted to receive a running rail and a guard rail and provided with recesses 10 along their overlapped margins to receive the inner base flanges of the rails, and with a rail-bearing shoulder against which the outer rail flange of the guard rail is adapted to bear, and a brace extending from said 15 overlapped margins to a point above and laterally removed from said overlapped margins to stand beneath the ball of the running rail supported by the plate.
2. The combination with a standard running rail and a standard guard rail, of a tie plate comprising a unitary structure and consisting of a pair of rail seats, the guard rail seat being in a plane above and its inner 20

margin overlapping the inner margin of the running rail seat, a lip rising from the plate 25 over said overlapped seat margins, a brace extending from said lip to the ball of the running rail, there being recesses to receive the inner, overlapped margins of both rails and rail bearing shoulders arising from 30 said seats in opposition to said recesses, said shoulders and recesses holding both rails against lateral movement to prevent spike shearing and said brace shifting the load strains on the running rail to the center of 35 the plate and the lateral strains of the guard rail to the ball of the running rail in order to prevent plate buckling and breaking.

In testimony whereof, I have signed my name to this specification, in presence of two 40 subscribing witnesses.

BENJAMIN B. BETTS.

Witnesses:

E. L. WALLACE,
E. M. HARRINGTON.
